PREPARATION OF 2-CHLOR-META-5-XYLENOL

George William Gladden, Oswaldtwistle, England,
assignor to William Wiggins Cocker, Accrington,
England

No Drawing. Application May 8, 1940, Serial No.
334,089. In Great Britain May 20, 1939

2 Claims. (Cl. 260—623)

This invention relates to improvements in preparation of 2-chlor-meta-5-xlenol, i. e. 1:3-dimethyl-2-chlor-5-hydroxybenzene.

This substance, which is useful as an antiseptic, is usually prepared by the chlorination of meta-xlenol (1—3—5), which is obtained by working up and crystallizing an intermediate xlenol fraction in the distillation of a suitable commercial cresylic acid containing xlenols.

According to the present invention we subject the crude intermediate obtained as a fraction in distillation of tar acids and containing meta xlenol to direct chlorination without previous isolation of meta-xlenol, and then separate the derivative desired e. g. 2-chlor-meta-5-xlenol.

This has the advantage of avoiding the tedious purification of the meta xlenol, and usually higher yields of the desired chlor-body can be obtained since it appears that the crude meta xlenol intermediate usually contains more meta-xlenol than it is possible to isolate by crystallization, and that the corresponding chlor-body can be isolated from the chlorination product with less loss.

It might have been expected that this process would increase the difficulty of purification on account of possible chlorination of impurities, but in practice this apparent difficulty is not usually observed.

It appears that the success of this method of isolation is dependent on the reactivity of the meta-xlenol, and the relative insolubility of the final product in the reaction mixture.

The intermediate may be any distillation fraction containing substantial quantities of meta-xlenol, e. g. say 10 to 20% by weight capable of isolation by crystallization alone, though the actual content of meta-xlenol may be much higher.

Intermediate fractions which will give 22 to 25% by weight of technical meta-xlenol m. p. about 60 deg. C. when worked up by crystallization alone can conveniently be used for this process. Such a fraction when chlorinated in the manner described later, can be made to yield 37 to 40% by weight of material substantially 2-chlor-meta-5-xlenol having a melting point of 112 to 115° C. Fractions containing greater quantities of meta-xlenol can be worked by the process quite conveniently and the limiting higher concentration of meta xlenol that could be used is dependent on the relative ease of isolation of such a fraction. It would be possible by means of extraordinary care, or by adding crystalline meta xlenol to the intermediate to make mixtures

which would contain very substantial quantities of meta-xlenol. There is no doubt that with such fractions, and with obvious modifications this method could be applied. The invention is mainly concerned only with fractions that can be more easily obtained and examples of such fractions and their isolation to the final product will be given later.

Chlorination can be accomplished by the direct action of chlorine on the intermediate fraction, the chlorine being passed into the material from cylinders or produced in situ in any obvious way, but we prefer to use sulphuryl chloride as better yields can be obtained using this material.

15 The determination of meta-xlenol in tar acid containing that material is not easy, and there does not appear to be any reliable and convenient method of estimation. It has therefore been necessary to use rather empirical methods for

20 the determination of suitable material, which, while they give us no actual indication of the amount of meta-xlenol present, they do give a measure by which we can assess the raw material. Earlier work on this intermediate was con-

25 centrated on fractions that would respond to a certain method of testing. In further examination of various intermediates it was found that another test can be usefully applied. Suitable materials are defined as follows:

30 They are essentially intermediates in the manufacture of meta xlenol and have a distillation range between 218 and 222 deg. C. at 760 mms. Hg. pressure, and having a crystallizing point of 20 degrees centigrade or better. The preferred material can be further defined in one of two methods:

Method 1

If equal weights of the intermediate and meta-5-xlenol are taken and heated together in a tube until the tube is filled with vapour and any water expelled and allowed to cool, the freezing point will be about 45 deg. C. or better. In the cooling, precautions must be taken to prevent any water being absorbed, the usual method being to plug the end of the tube with a calcium chloride trap. Furthermore, the meta-5-xlenol used in the above test should have a freezing point of at least 64 deg. C.

Method 2

A suitable quantity of the meta-xlenol intermediate is taken and placed in a tube and carefully heated to expel water vapour and cooled, precautions being taken to avoid any absorption of water by means of a suitable trap such as one

containing calcium chloride. The intermediate is allowed to crystallise with stirring. If the material is not supercooled too far it will be found that the heat of crystallisation of the metaxylenol is usually sufficiently great to cause the material to melt again after a suitable lapse of time. As the liquid melts it becomes clearer and a point is reached when the turbidity just disappears, the contents of the tube being stirred throughout the whole operation. If the test is carried out correctly, this point is quite sharp and the temperature is noted. Two or three estimations should be done to ensure that the correct point has been obtained. A melting point of 25°-33° C. is desirable.

Broadly speaking the preferred intermediates are those which comply with the above tests. But we may use any intermediate obtained from tar acids by distillation alone, i. e. without further or substantial further purification by crystallisation. The intermediate might be enriched by addition of pure metaxylenol but a major proportion of distillate would be present and in any case any addition of pure metaxylenol would usually be pointless.

EXAMPLE 1

546 grams of intermediate xlenol fraction (having a crystallising point of 45° C., when mixed with an equal weight of meta-5-xlenol as defined in method (1)) are placed in a suitable vessel, equipped with stirring gear and 273 grams of sulphuryl chloride are added slowly. The temperature rises in the course of the reaction to about 40° C. When all the sulphuryl chloride is added the reaction mixture is heated to 80° C. and the acid gases removed as far as possible by air-blowing or any other suitable means. On cooling a quantity of the required chlor xlenol separates out and is removed from the mother liquor. Further quantities of the material required can be isolated by vacuum distillation of the mother liquors and further crystallisation. In all 200 to 208 grams of material substantially 2-chlor meta-5-xlenol can be obtained having a melting point of 112 to 115° C. The material can be purified if desired by crystallisation from a solvent such as a hydrocarbon.

EXAMPLE 2

100 grams of a meta-xlenol intermediate (having a crystallising point of 45.75° C. when mixed with an equal weight of meta-5-xlenol as defined by method (1)), is placed in a suitable vessel and 31.6 grams of chlorine passed in, in about 30 to 40 minutes, the temperature being kept between 25-30° C. during the course of the reaction. The chlorine is determined as accurately as possible by means of a flow-motor. A yield of 25 grams of the desired product is obtained when heated up, acid gases removed and crystallised as in Example (1).

When a further 100 grams of the same metaxylenol intermediate is treated with 60 grams of sulphuryl chloride at approximately the same temperature, and using the same method of isolation, a yield of 37 to 40 grams of the desired product is obtained. (60 grams of sulphuryl chloride corresponds closely with 31.6 grams of chlorine).

EXAMPLE 3

10 1165 lbs. of an intermediate meta-xlenol fraction as above defined and having a melting point of 31.25° C. (see method (2)), are placed in a suitable vessel, equipped with means for agitation and with provision for heating and cooling. The vessel is also preferably closed and provision made for the escape of acid vapours and for the running in of sulphuryl chloride. Further, it is very desirable that the vessel and component parts should be fabricated in acid resisting material, or alternatively lined with acid resisting material.

15 The temperature of the charge in the vessel is maintained at a temperature which will just keep the material in solution and 833 lbs. of sulphuryl chloride are added with agitation during the course of 6 to 7 hours. During the course of the addition the temperature tends to rise and the reaction mass may have to be cooled. It is desirable that the temperature during this part of the process should be kept between 30 and 40° C. 20 The batch is then heated to 80° C. and the acid gases removed as far as possible by air blowing, or other suitable means. On cooling to 18° C. or lower, the desired chlor-xlenol separates out and can be removed from the mother liquor by the usual means such as filtration or by means of a centrifuge. The crystals are then washed with 25 18 to 20 gallons of benzene.

30 The average yield on five batches treated in this manner was 522 lbs. of material melting at about 114° C.

35 I declare that what I claim is:

40 1. The process of preparing 1:3-dimethyl-2-chlor-5-hydroxybenzene which consists in treating a crude metaxylenol tar acid fraction, containing a large proportion of impurities and having a distillation range between 218° C. and 222° C. at 760 mm. Hg, with a chlorinating agent selected from the group consisting of elementary chlorine and sulphuryl chloride capable of producing the 2-chloro derivative and separating said 2-chloro derivative by crystallisation.

45 2. The process of preparing 1:3 dimethyl-2-chloro-5-hydroxybenzene which consists in reacting a crude metaxylenol tar acid fraction, containing a large proportion of impurities and having a distillation range between 218° C. and 222° C. at 760 mm. Hg. with sulphuryl chloride and separating crystals of the desired 2-chloro body by cooling the hot reaction-mixture.

50 60 GEORGE WILLIAM GLADDEN.
